UNITED STATES PATENT OFFICE

2,679,883

COLUMN FLUTING ROLLER MECHANISM

Hans Guthmann, Pasadena, Md.

Original application March 16, 1949, Serial No. 81,698, now Patent No. 2,568,730, dated September 25, 1951. Divided and this application August 1, 1951, Serial No. 239,803

2 Claims. (Cl. 153—70)

1

This invention relates to new and useful improvements in fluting machines and more particularly pertains to a roller mechanism disclosed in my copending application, Serial No. 81,698, filed March 16, 1949, now U. S. Patent No. 2,568,730, issued September 25, 1951, of which this is a division.

An important object of the present invention is to provide a machine for fluting metal columns including a plurality of radially movable roller units for pressing against a metal column so that groups or recesses of a predetermined depth may be formed in the column.

A further object of the present invention is to provide an improved fluting roller unit and a hydraulic cylinder and piston mechanism for operating the same.

Other objects and advantages reside in the details of construction and operation as more fully hereinafter described and claimed, reference being had to the accompanying drawing forming a part hereof, wherein like numerals refer to like parts throughout, and in which:

Figure 1 is an elevational view of the present invention, parts being broken away, and showing in use the apparatus of my prior patent of which the instant invention forms a part;

Figure 2 is an enlarged, fragmentary, vertical sectional view of the hydraulic control means for the fluting rollers which constitute the invention claimed hereinafter; and

Figure 3 is an enlarged detailed view of a portion of Figure 2.

Figure 1 shows the general arrangement of the apparatus of which the roller mechanism of Figure 2 forms an essential component. The apparatus itself is set forth in detail and is claimed in my prior above identified patent, and the structure and operation of the apparatus has been disclosed in the present application with only sufficient detail to provide a clear understanding of the environment in which the roller mechanism claimed herein is primarily intended for use. The same numerals are employed to identify the same elements in the present application and in my prior patent.

Referring now to Figure 1, which is a duplicate of Figure 1 of my prior above identified patent, a support including a pair of parallel H-beams or I-beams 42 rises from a base construction 26. A carriage 48 is mounted for vertical, guided movement on the beams 42 under the control of a hydraulically operated cylinder and piston unit. The latter includes a cylinder 54 secured to and carried by a cross-head 46 mounted upon the

2

beams 42, the cylinder 54 having a member 80 slidable therein, upon the lower end of which is secured the carriage 48.

Depending from the carriage 48 is an elongated and tapering, fluted cylindrical mandrel 10 upon which the fluting of an elongated sheet metal column 12 is to be performed.

The base construction includes a plurality of horizontally disposed fluting roller units positioned radially about the axis of the mandrel 10, which latter is movable vertically therebetween. These roller units press the material of the column 12 into the flutes of the mandrel 10 upon vertical travel of the mandrel and column between the fluting roller units to thus form flutes in the column. The means for controlling the pressure upon the roller units is set forth in my prior patent, forms no part of the invention claimed herein, and further discussion thereof appears to be unnecessary.

These units which are of identical construction, constitute the invention claimed hereinafter.

As shown in Figure 2, each of the fluting roller units comprises a cylindrical open-ended guide 25 casing 140 secured to and forming a part of the base construction 26, in which is slidably received a cylindrical slide 142 which rotatably supports a flute forming roller 144 having beveled edges.

The guide cylinders 140 have outer flanges to 30 which are secured, by means of bolts and nuts 158, inner and outer end flanges or plates 152 and 154 which are thus removably secured to the opposite open ends of the cylinders 156.

The end flanges or plates 152 and 154 are centrally apertured to slidably receive tubular piston rods 160 that support piston heads 162. The piston heads 162 (see Figure 3) support flexible, channel-shaped sealing rings 164 on both their faces that will expand during movement of the piston rods 160 and piston heads 162 to prevent a fluid within the cylinders 156 from passing between the inner peripheries of the cylinders 156 and the outer peripheries of the piston heads 162.

Rings 166 are provided on the inner faces of 45 the end plates 152 and 154 and are spaced from the outer peripheries of the piston rods 160. Flexible, channel-shaped sealing rings 168 bear against the inner faces of the end plates 152 and 154 and are disposed between the outer peripheries of the piston rods 160 and the rings 166 to prevent a fluid within the cylinders 156 from passing between piston rods 160 and the end plates 152 and 154 and outwardly of the cylinders 156 and further flexible sealing rings 167 are re-

ceived in channels 169 provided in the rings 166 and bear against the cylinders 156.

Rods 170 are received in the piston rods 160 and are threaded to the slides 142. The outer head ends 172 of the rods 170 abut the outer ends of the piston rods 160 so that the rods 170 and slides 142 will be moved with the piston rods 160.

The outer ends of the piston rods 160 are threaded to receive adjustable stops or nuts 174 that will engage the end plates 154 to limit the inward sliding movement of the members 142.

Each of the cylinders 156 is provided with a pair of combined inlet and outlet ports, not shown, that are connected by branch pipes 178 to a supply and control system of any desired character such as that indicated generally by the numeral 181.

By the selective application of fluid pressure from the system 181 to the opposite sides of the piston 162, for example in the manner set forth and described in my above identified prior patent, it will be evident that the fluting rollers can be moved inwardly or outwardly to control the fluting operation, and the extent of the inward movement of the rollers can be adjusted by the adjusting nut 174.

An important feature of the invention is the manner in which the parts can be conveniently serviced for inspection or replacement of the leather rings used or the other parts, and in this regard, it is noted that the sealing rings will expand or spread in response to an internal pressure in the cylinders where the same are employed.

Having described the invention, what is claimed as new is:

1. A fluting roller unit comprising an open ended casing having a flanged outer end, a cylinder 5 having inner and outer end plates, means securing the end plates to the flanged portion, a tubular piston rod extending axially through the cylinder and centrally through the end plates and including inner and outer ends, a roller holding slide received in the casing and engaged by the inner end of said piston rod, a rod element secured to the slide and extending completely axially through the piston rod and having an outer enlarged end disposed outwardly from the outer end of the piston rod, a piston head fixed on the rod and disposed within the cylinder, fluid pressure means connected to the cylinder for moving the piston within the cylinder, and an adjustable stop nut threaded on the outer end of the piston 10 rod engageable with the outer end plate to limit sliding movement of the piston rod relative to the cylinder.

2. The combination of claim 1 and sealing means carried by each of said end plates engaging 15 the inner periphery of said cylinder and the outer periphery of said piston rod.
